METHOD OF FORMING PISTON RINGS

William Wuerfel, Philadelphia, Pa., assignor to
George Kessler, Philadelphia, Pa.

Application September 3, 1935, Serial No. 38,951

3 Claims. (Cl. 148—21.5)

The object of my present invention is to devise a novel method of and apparatus for forming piston rings.

In the manufacture of piston rings it has been customary to so construct the piston ring that it would have uniform radial pressure. It has been found recently that piston rings with uniform radial pressure have a tendency to flutter at the ends near the gap. In the modern high speed, high compression engines, this fluttering action permits the burned gases to blow by the rings to such an extent that the rings are burned.

Piston ring manufacturers are now experimenting to produce a piston ring that has a greater unit pressure at the gap than at other points of its circumference. This is a difficult problem because no point of the circumference can be of minus pressure. This means that the piston ring must be light tight.

With the above in view, my invention comprehends a novel method of and apparatus for forming piston rings which will produce the form or shape necessary to provide the desired pressures for modern engines.

It further comprehends a novel method of and apparatus for forming piston rings wherein by changing the dimensions of the different components of the apparatus, the pressure at any point of the circumference of the ring can be varied.

Other novel features of construction and advantage will hereinafter more clearly appear in the detailed description and the appended claims.

For the purpose of illustrating the invention, I have shown in the accompanying drawing a typical embodiment of it, which, in practice, will give satisfactory and reliable results. It is, however, to be understood that the various instrumentalities of which my invention consists can be variously arranged and organized, and my invention is not limited to the exact arrangement and organization of these instrumentalities as herein set forth.

Figure 1 is a top plan view of an apparatus which may be advantageously employed in carrying out my method, and illustrated in conjunction with a piston ring.

Figure 2 is a top plan view of the apparatus.

Figure 3 is a side elevation of the apparatus with the piston rings in place.

Figure 4 is a side elevation of the apparatus.

Figure 5 is a top plan view of a finished piston ring.

Figure 6 is a top plan view of a split piston ring before being placed on the former.

Similar numerals indicate corresponding parts.

Referring to the drawing:

Referring first to Figures 2 and 4, the apparatus comprehends a form 1, which acts as a spreader, and which is turned down to provide a cylindrical forming surface 2 and an annular shoulder 3. 4 is a spacer or spreader adjustably connected to the body portion by a fastening device 5, such as a bolt and nut, so as to provide for the use of spacers or spreaders of different widths.

6 designates the piston rings which are to be formed, in accordance with my present invention, and which are in the form of cylindrical split rings.

In carrying out my novel method, the piston rings are mounted on the form, as shown in Figures 1 and 3, and the spacer 4 forms a predetermined gap between the free ends of the rings. The rings while on the form, are heated to a suitable temperature for the proper length of time depending on the character of material used in making the rings. After the rings have been heated, they may be left to cool in the atmosphere or they may be quenched. Piston rings made by this method have the desired form in a pressure gage. The important component parts are a form and a spacer or spreader. Each of these have a definite effect on the form of the finished ring.

To increase the roundness of the ring, I increase the width of the spreader 4. To increase the plus pressure at the gap I increase the diameter of the form. This variation can be kept to very close limits in either direction depending upon the result desired. The rings produced by this method can be grooved, channeled, slotted or drilled and still be held to the desired or predetermined form or contour. In this manner, piston rings which are dished, or which have been subjected to special operations can be produced without materially changing their form. If it is found that any previous or future operation affects the form of the finished piston ring, it can be corrected by varying the components of the former.

It will be apparent from the foregoing, that in accordance with this invention, one is enabled to produce a piston ring which will have the requisite form or shape to give the pressures desired for modern engines.

In Figure 5, I have shown a piston ring in detached position, to indicate more clearly the gap which is produced and maintained during the heat treatment. It is to be understood that this

gap will vary in accordance with conditions and requirements met with in practice.

In Figure 6 I have shown the completed ring.

It will be understood that while I have shown the form in the drawing for the purpose of illustrating only one form of my invention as being circular, that the form may have any contour which will impart to and maintain the desired contour of the ring during heat treatment.

10 It will now be apparent that I have devised a new and useful method of and apparatus for forming piston rings which embodies the features of advantage enumerated as desirable in the statement of the invention and the above description, and while I have, in the present instance, shown and described a preferred embodiment thereof which will give in practice satisfactory and reliable results, it is to be understood that this embodiment is susceptible to modification in various 20 particulars without departing from the spirit or scope of the invention or sacrificing any of its advantages.

Having thus described my invention, what I claim as new and desire to secure by Letters 25 Patent is:—

1. The method of forming a piston ring, which consists in stretching a split ring over a spreader with a gap former between the free ends of the ring and with the free ends of the ring exerting a pressure against opposite sides of the gap former,

and with the free ends of the ring and diametrically opposite portions of the ring exerting pressure against the spreader, and subjecting the ring in such condition to heat treatment to produce a formed ring having plus pressure at the gap.

2. The method of forming a piston ring, which consists in stretching a split ring over a spreader to increase the width of the ring between the free ends and opposite portions of the ring, and having the free ends of the ring exerting a pressure 10 against opposite sides of a gap former, with only the free end portions and opposite portions thereto of the ring exerting a pressure against the spreader, and subjecting the ring while in such shape on the spreader to heat treatment to produce a 15 ring having plus pressure at the gap.

3. The method of forming a piston ring, which consists in stretching a split piston ring over a spreader of a width relative to the free ends of the ring and portions of the ring opposite thereto 20 which will define a determined plus pressure at the gap of the ring, at the same time exerting pressure of the free ends of the ring against a gap former of a width to give a determined roundness of the ring, and subjecting the ring 25 while in such shape on the former to heat treatment to produce a piston ring having a predetermined roundness, and having predetermined plus pressure at the gap.
